HUBBARD N. JOSLEYN, OF SYRACUSE, NEW YORK, ASSIGNOR TO THE MONARCH TYPE-WRITER COMPANY, OF SYRACUSE, NEW YORK, A CORPORATION OF NEW YORK.

TYPE-WRITING MACHINE.

1,054,847.

Specification of Letters Patent.

Patented Mar. 4, 1913.

Application filed July 29, 1909. Serial No. 510,252.

To all whom it may concern:

Be it known that I, HUBBARD N. JOSLEYN, a citizen of the United States, and resident of Syracuse, in the county of Onondaga and State of New York, have invented certain new and useful Improvements in Type-Writing Machines, of which the following is a specification.

My invention relates more particularly to the bearings for the type bars of type-writing machines, and has for its main object to provide an improved construction of type bar hanger and one which while occupying a small space laterally considered, yet, at the same time, furnishes a broad and stable bearing for the type bar.

To these ends the invention consists in the features of construction, combinations of devices and arrangements of parts to be hereinafter fully described and particularly pointed out in the claims.

In the accompanying drawings, Figure 1 is a fragmentary sectional view, taken about centrally, of a typewriting machine embodying my invention, parts of the machine being omitted. Fig. 2 is a fragmentary front elevation taken on a plane represented by the line $x-x$ in Fig. 1, some parts not shown in said Fig. 1 being added and other parts shown in said Fig. 1 being omitted. Fig. 3 is an enlarged sectional view, taken on a horizontal plane passing through the center of rotation of the type bar shown in Fig. 1. Fig. 4 is a fragmentary view of the type bar and hanger taken on a plane represented by the line $y-y$ in Fig. 3. Fig. 5 is a detail view of the type bar bearing plates.

In the drawings the main frame of the machine is shown as comprising a base 1, corner posts 2 and a top plate 3. Key levers 4 are fulcrumed at 5 in the rear of the base, each of said key levers being provided with a restoring spring 6. Pivotaly connected at 7 with each key lever is a sub-lever 8, the lower end whereof is slotted to co-act with a fixed abutment 9 and the upper end whereof is connected by a link 10 with a type bar 11 which is mounted in a manner presently to be described in a type bar hanger 12. The hanger 12 is one of a series of hangers segmentally arranged in radial slots or kerfs 13 formed in the front face of a segmental

type bar support 14. The segmental support 14 is connected with a known form of shifting mechanism, but for the purposes of this invention it is immaterial whether the segment 14 be shiftable or nonshiftable; and the type bars are designed to move upwardly and rearwardly to co-act with the front face of a platen 15, but considered in its broader aspects it is immaterial for my purposes whether the invention is embodied in a front-strike typewriting machine, as shown, or in some other kind or style of writing machine.

Each hanger 12 is bifurcated, the bifurcations or side walls 16 and 17 being joined at the bottom by a web or base portion 18 from which depends a shank or stem 19 provided with a cam slot 20. The shank or stem 19 of each hanger fits into one of the radial slots 13 in the segmental support 14, and the cam slot 20 receives a set screw 21 by which the hanger is secured in place, the end of said set screw abutting the cam portion of the slot 20 so that as said set screw is screwed in tight it serves to firmly seat the hanger with the web 18 in contact with the top of the segment 14.

The side walls 16 and 17 of the hanger are perforated to receive a plurality of rivets 22, which are preferably four in number. Two bearing plates 23 substantially sectoral in shape, have their outer circularly curved edges formed with a double beveled portion 24 and their inner circularly curved edges formed centrally with a single beveled portion 25 having a greater inclination than the bevels 24. Each bearing plate is formed with perforations 26 somewhat larger in diameter than the rivets 22, said rivets passing through the perforations 26 and serving to connect the bearing plates loosely with the side walls of the hanger. An adjusting screw 27 having a head coned on the under side passes from the wall 16 to the wall 17 of the hanger, being received in perforations in said walls and being arranged so that the coned portion of the head contacts with the beveled portions 25 of the bearing plates 23. It will be noted that the perforation for the screw 27 in the plate 17 is threaded to receive the threaded shank of said screw, while the head of the

screw passes through a larger plain perforation in the wall 16. The pivotal end of the type bar 11 is provided with an eye 28, the edge of which is formed with a V-shaped groove 29 which receives the outer beveled edges 24 of the bearing plates 23.

In assembling the parts the bearing plates 23 are preferably inserted in the eye 28 in the type bar 11 which is then positioned between the bearing walls 16 and 17 of the eyeless member or hanger. It will be noted from an inspection of Fig. 3 that the bearing plates 23 are of such width that they fit snugly between the hanger walls 16 and 17, while the type bar is somewhat narrower and does not contact with the inner faces of said hanger walls. The rivets 22 are next passed from one bearing wall to the other and through the perforations 26 in the bearing plates, after which said rivets are headed so that the bearing plates are loosely but permanently mounted in the hanger. The adjusting screw 27 is then screwed into place, the coned portion of said screw acting on the beveled edges 25 to cam the bearing plates 23 outwardly or away from the axis of rotation so that the beveled edges 24 of the bearing plates engage the V-shaped groove 29 in the eye 28 of the type bar in such wise that said type bar may turn freely on the bearing plates, although the fit is sufficiently snug to take up all unnecessary looseness and to maintain the type bar properly aligned.

In order to take up wear between the bearing plates and the type bar it is only necessary to tighten the adjusting screw 27, thereby causing the bearing plates to move outwardly in the eye of the type bar, such movement being possible because of the fact that the perforations 26 are somewhat larger than the rivets 22.

It will be observed that the bearing plates are at diametrically opposite sides of the axis of rotation of the type bar; that said bearing plates are in the same plane transverse of said axis of rotation; that said plane is the median plane of the type bar; that the bearing plates are adjustable in said plane and transversely of the axis of said type bar; that the type bar hangers as I construct them are comparatively narrow so that they may be assembled close together on the segment, as best seen in Fig. 2, while at the same time they provide a wide bearing for the type bars, thus conducing to the stability of the latter; that by my invention a type bar hanger is provided having a bearing part or parts attached to it and coöoperating with the eye in the type bar and movable away from the axis of motion by means separate from the means which support the part or parts, which parts in the present instance are two opposing bearing devices or sectoral bearing

plates constituting together an expandible disk.

Various changes in the construction and arrangement of the parts may be effected within the scope of the invention.

What I claim as new and desire to secure by Letters Patent, is:—

1. In a typewriting machine, the combination of a hanger, a bearing plate attached thereto, a second bearing plate, and a type bar having an eye in which said first named bearing plate engages and in which it is bodily movable away from the axis of rotation of the type bar.

2. In a typewriting machine, the combination of a hanger, a bearing plate, means for connecting said bearing plate to said hanger, a type bar having an eye in which said bearing plate engages, a bearing part opposing said bearing plate and engaging in said guide, and separate means for adjusting said bearing plate in the eye of the type bar, the adjustment of said bearing plate being independent of the movement of the hanger.

3. In a typewriting machine, the combination of a hanger having parallel walls, a pair of bearing plates mounted independently of each other between said walls, and a type bar having an eye in which said bearing plates engage, said bearing plates being each movable toward and away from the axis of rotation of said type bar.

4. In a typewriting machine, the combination of a hanger having parallel walls, a pair of bearing plates loosely secured independently of each other to said walls, a type bar having an eye in which said bearing plates engage, and means for adjusting said bearing plates in the eye of the type bar independently of movement of the supporting hanger walls.

5. In a typewriting machine, the combination of a type bar hanger having parallel walls, rivets connecting said walls, a pair of bearing plates loosely mounted on said rivets between said walls, a type bar having an eye in which said bearing plates engage, and an adjustable screw operable on said plates to regulate their engagement with the type bar.

6. In a typewriting machine, the combination of a hanger having parallel walls, rivets connecting said walls, a pair of bearing plates mounted on said rivets and having beveled edges, a type bar having an eye bounded by a V-shaped groove in which the beveled edges of said bearing plates engage, and means operable on said plates to regulate their engagement with the V-shaped groove.

7. In a typewriting machine, the combination of a hanger having parallel walls, rivets connecting said walls, a pair of bearing plates loosely mounted on said rivets,

5 said bearing plates having outer and inner beveled edges, a type bar having an eye bounded by a V-shaped groove in which the outer beveled edges of the bearing plates engage, a coned adjusting screw engaging the inner beveled edges of said plates and operable thereon to force them outwardly in the eye of the type bar.

10 8. In a typewriting machine, the combination of a bifurcated hanger having a depending stem; bearing plates mounted independently of each other between the bifurcated portions of said hanger, and a type bar having an eye in which said bearing plates engage and in which said bearing plates are movable independently of each other toward and away from the axis of rotation of said type bar.

15 9. In a typewriting machine, the combination of a bifurcated hanger having a depending stem, bearing plates mounted between the bifurcated portions of said hanger, a type bar having an eye in which said bearing plates engage, and means operable on said plates to regulate their engagement with the type bar, said means being movable to effect such regulation independently of movement of the bifurcated portions of said hanger.

20 10. In a typewriting machine, the combination of a bifurcated hanger having a depending stem, rivets connecting the bifurcated portions of said hanger, a pair of bearing plates loosely mounted on said rivets, a type bar having an eye in which said bearing plates engage, and an adjustable screw contacting with said plates and operable thereon to force them outwardly in the eye of said type bar.

25 11. In a typewriting machine, the combination of a slotted type bar support, a series of bifurcated hangers having depending stems, which stems fit into the slots in said support, bearing plates mounted between the bifurcated portions of said hangers, and type bars having eyes in which said bearing plates engage, said bearing plates being movable in the planes of their type bars.

30 12. In a front-strike typewriting machine, the combination of a slotted type bar supporting segment, a series of bifurcated hangers having depending stems secured in the slots of said segment, rivets connecting the bifurcated portions of said hangers, bearing plates loosely mounted on said rivets, type bars having eyes engaged by said bearing plates, and screws operable on said bearing plates to regulate their engagement with the type bars.

35 13. In a typewriting machine, the combination of a type bar having an eye, a type bar hanger, a bearing part attached to said hanger and coöperative with the eye in the type bar, said part being movable out-

wardly in the eye and away from the axis of motion of the type bar to take up wear, and an opposing bearing part coöperative with the eye in the type bar.

40 14. In a typewriting machine, the combination of a type bar having an eye, a type bar hanger, and two bearing parts separately and independently attached to said hanger and coöperative with the eye in the type bar, said parts being movable outwardly in the eye and away from the axis of motion of the type bar to take up wear.

45 15. In a typewriting machine, the combination of a type bar having an eye, a type bar hanger, and two bearing parts attached to said hanger and coöperative with the eye in the type bar, said parts being movable away from each other and from the axis of motion of the type bar to take up wear.

50 16. In a typewriting machine, the combination of a type bar having an eye, a type bar hanger having parallel bearing walls, a bearing plate coöperative with the eye in the type bar, means connecting said bearing walls and supporting said bearing plate, separate means for adjusting said bearing plate in the eye in the type bar, and a bearing part associated with said bearing plate and also coöperative with the eye in the type bar.

55 17. In a typewriting machine, the combination of a type bar having an eye, a type bar hanger having parallel bearing walls, a bearing plate coöperative with the eye in the type bar, means connecting said bearing walls and supporting said bearing plate, separate means for moving said bearing plate outwardly in the eye in the type bar and away from the axis of motion, and a bearing part associated with said bearing plate and also coöperative with the eye in the type bar.

60 18. In a typewriting machine, the combination of a type bar having an eye, a type bar hanger having parallel bearing walls, bearing plates coöperative with the eye in the type bar, means connecting the hanger walls and supporting said bearing plates, and means for moving said bearing plates away from each other in the eye in the type bar.

65 19. In a typewriting machine, the combination of a type bar having an eye, a type bar hanger, and a pair of sectoral bearing plates supported on said hanger and radially adjustable in the eye in the type bar.

70 20. In a typewriting machine, the combination of a hanger, an expansible bearing-disk secured thereto, a type bar having an eye engaged with said bearing-disk, and means for expanding the bearing-disk.

75 21. In a typewriting machine, the combination of a hanger, an expansible bearing-disk secured thereto, a type bar hav-

- ing an eye containing a groove in which the bearing disk fits, and means for expanding the bearing disk. 50
22. In a typewriting machine, the combination with a pivotal type bar and a type bar hanger, one of said parts having an eye, of a bearing plate arranged within said eye and attached to the eyeless part, means for adjusting said plate transversely of the pivotal axis of the type bar, and a second bearing plate arranged within said eye. 55
23. In a typewriting machine, the combination with a type bar and a type bar hanger, one of said parts having an eye and the other parallel walls, of a pair of bearing plates arranged within said eye and adjustably supported by said walls, and means for adjusting said plates in opposite directions transversely of the axis of motion 60 of said type bar.
24. In a typewriting machine, the combination with a type bar and a type bar hanger, one of said parts having an eye and the other part having walls which are parallel with each other and which embrace between them the part having the eye, of a pair of bearing plates arranged within said eye and adjustably supported by said walls, and a coned adjusting screw engaging said 65 plates and operative to move said plates relatively to the hanger walls which support the same. 70
25. In a typewriting machine, the combination of a hanger, a bearing plate supported by said hanger, a type bar having an eye which receives said bearing plate, said bearing plate lying in the median plane of the type bar, relative movement between said type bar and said bearing plate taking 75 place during printing operations, and a bearing part opposing said bearing plate and also arranged within the eye of the type bar. 80
26. In a typewriting machine, the combination of a hanger, a bearing plate loosely supported by said hanger, a type bar having an eye with which said bearing plate engages, said bearing plate lying in the median plane of the type bar, the hanger, type bar and bearing plate being relatively movable one to another, relative movements between said type bar and said bearing plate taking place during printing operations, and a second bearing plate engaging in the eye in the type bar. 85
27. In a typewriting machine, the combination with a hanger and a type bar, one of said parts having an eye, of bearing plates connected to the other part and received within said eye, said bearing plates being at diametrically opposite sides of the axis of rotation of the type bar. 90
28. In a typewriting machine, the combination of a hanger, a pair of bearing plates supported by said hanger, and a type bar having an eye which receives said bearing plates, said bearing plates being at diametrically opposite sides of the axis of rotation of the type bar and in the same plane transverse of said axis. 95
29. In a typewriting machine, the combination of a hanger having parallel bearing walls, bearing plates mounted between said walls, and a type bar having an eye with which said bearing plates engage at opposite sides of the axis of rotation of the platen. 100
30. In a typewriting machine, the combination with a type bar and a hanger, one of said parts having parallel bearing walls and the other of said parts having an eye, of a bearing plate co-operative with said eye, means connected to said bearing walls and supporting said bearing plate, a second bearing plate, and separate means for adjusting said first named bearing plate independently of movement of said bearing walls. 105

Signed at Syracuse in the county of Onondaga and State of New York this 27th day of July A. D. 1909.

HUBBARD N. JOSLEYN.
